(57) **CLAIM**

I claim, the ornamental design for a display screen or portion thereof with graphical user interface, as shown and described.

DESCRIPTION

FIG. 1 is a front view of a display screen or portion thereof with graphical user interface including a graphical user interface icon showing my new design; and, FIG. 2 is an enlarged partial view of the area defined by the dash-dot line shown in FIG. 1.

The dash-dash broken lines depict portions of a display screen with graphical user interface. The dash-dot broken lines illustrate the location and bounds of the enlarged partial view of FIG. 2. None of the broken lines form part of the claimed design.
